UNITED STATES PATENT OFFICE

EDWIN COULSON, OF CHISWICK, LONDON, ENGLAND

FEEDING MECHANISM OF SLICING MACHINES

Application filed May 7, 1928, Serial No. 275,925, and in Great Britain June 1, 1927.

This invention has reference to improvements in or relating to the feeding mechanism of slicing machines.

In connection with slicing machines it is usual to provide the slicing table with a feed screw and nut mechanism for permitting of the rapid initial adjustment of the meat relatively to the knife edge prior to the commencement of a slicing operation and it is found in practice that in effecting the aforesaid adjustment it frequently happens that the feed screw is rotated too far with the result that the nut becomes disengaged from the thread of the screw thereby necessitating a relatively tedious operation before the re-engagement of the nut and the thread of the screw can be obtained. In connection with slicing machines it is found desirable also that the slicing table should be capable of being readily detached from the machine in order to permit of the cleansing of the table and the inspection of the track when required.

The present invention has for its objects the provision of an improved means for permitting of the ready re-engagement of the components of the initial adjusting feed mechanism in the event of their inadvertent disengagement and the provision of means for permitting of a ready detachment of the slicing table from the slicing machine when desired.

The invention consists of an improved feed mechanism of the kind hereinbefore referred to for use with slicing machines characterized by the provision in conjunction with the feed screw nut of a worm wheel adapted to engage with the thread of the feed screw and to be capable of rotation upon the operation of the said screw only in a one way direction whereby in the event of the disengagement of the nut from the feed screw a rotation of the feed screw in an opposite direction entails a locking of the worm wheel against rotation and subsequently causes the said wheel to be traversed along the screw thereby drawing the nut into re-engagement with the feed screw.

The invention also resides in the provision of means for freeing the nut from the feed

screw and for unlocking a slicing table latching means whereby the slicing table can be readily removed from the slicing machine when desired.

The invention will now be described with particular reference to the accompanying sheet of drawings, wherein:

Figure 1 is a part sectional side elevation of the traversing mechanism for the slicing table.

Figure 2 is a detail view showing the nut for the slicing table traversing mechanism and a portion of the feed screw.

Figure 3 is a side elevation illustrating the manner of securing the slicing table to the carriage, and

Figure 4 is a detail view of the latch mechanism for securing the rear end of the slicing table to the carriage.

The slicing table is provided adjacent its slide with a nut 5 the threaded portion 5^a whereof engages with a correspondingly threaded portion 6^a rotatably mounted in bearings supported from the carriage and parallelly disposed relative to the path of the slicing table. The aforesaid nut is provided with a forwardly extending portion 5^b which carries a spindle 8 having rotatably mounted thereon a worm wheel 7 adapted to mesh with the feed screw 6. The teeth of the said worm wheel are engaged also by the nose of a spring operated one way detent 9 which permits of the rotation of the worm wheel in a clockwise direction only.

The nut is normally maintained in engagement with the feed screw 6 by means of a spring 10 one end whereof bears upon the upper surface of the nut.

At one side the nut 5 is provided with a lateral projection 5^c the underside of which engages a crank 11 fixed on the end of a shaft 12 rotatably mounted relatively to the carriage. The aforesaid shaft 12 has secured thereto at one end an upwardly projecting arm 13 whereby by gripping the fixed handle 16 by the hand and engaging the thumb of the same hand with the arm 13 the shaft 13 may be rocked as and for a purpose to be set forth hereinafter. The arm 13 is carried by a cylindrical boss 13^b of a greater diameter

than the shaft 12 said boss 13^b having formed therein a helical slot 13^a within which engages a pin 14^a connected to a latch 14 which in its locking position engages a latch formed on the slicing table 15. It will be seen that upon rotating the shaft 12 the boss 13^b is rocked therewith whereby the edges of the slot bear on the adjacent faces of the pin 14^a and move the pin and hence the latch carried thereby in the direction of the arrow indicated in Figure 4.

The operation of the invention is as follows:—

In the event of the feed screw 6 being traversed too far and thereby occasioning a disengagement of the nut 5 from the feed screw the continued rotation of the feed screw 6 merely results in a rotation in a clockwise direction of the worm wheel 7 and thereby gives rise to a clicking noise which serves to warn the operator that the nut 5 is out of engagement with the feed screw 6. The feed screw 6 is thereupon rotated in the opposite direction by means of the handle 6^b whereby the worm wheel 7 is locked against rotation and is thus caused to move along the feed screw in the direction of the handle 6^b thereby dragging the nut 5 into re-engagement with the feed screw 6 whereupon the feed screw can be manipulated in the ordinary manner for effecting the adjustment of the slicing table 15. When it is desired to remove the slicing table 15 from the slicing machine the small operating lever 13 is pressed towards the right thereby effecting a rotation of the shaft 12 upon which it is mounted and thus of the crank 11 secured thereto whereby the said crank 11 is caused to bear on the underside of the projection 5^c on the nut and lift the said nut out of engagement with the feed screw, the lifting movement taking place in opposition to the coil spring 10. The continued rotation of the aforesaid operating lever 13 through the co-operation of the pin and helical slot mechanism effects a withdrawal of the latch 14 from the locking projection on the slicing table 15. The slicing table 15 is then free to be removed and permits of a ready cleansing of the table and also access to the track for inspection purposes.

Claims:—

1. A feed mechanism of the kind hereinbefore referred to for use with slicing machines comprising a slicing table, a rotatable feed screw, a feed screw nut fixed relatively to said slicing table and adapted to engage with said feed screw, a latching means for securing the table to the machine, a rotatable spindle, a crank arm carried by said spindle and adapted to bear on the underside of the feed screw nut, a projection on the latching means, a helical groove formed in the spindle within which the projection carried by the latching means is adapted to engage and

means for imparting a rotary movement to the spindle whereby the motion so imparted can be caused to rock the crank arm so as to lift the feed screw nut from engagement with the feed screw and so as to cause the projection connected to the latching means to travel in the helical groove in the spindle so as to unlock the said latching means.

2. A feed mechanism of the kind referred to for use with slicing machines comprising a slicing table, a rotatable feed screw, a feed screw nut fixed relatively to said slicing table and adapted to engage with said feed screw, a worm wheel carried by the slicing table and adapted to engage with the feed screw said worm wheel being capable of rotation in a one way direction only upon the rotation of the feed screw, whereby in the event of the disengagement of the feed screw nut from the feed screw a rotation of the feed screw in an opposite direction entails a locking of the worm wheel against rotation and subsequently causes the wheel to be traversed along the screw thereby drawing the feed screw nut into re-engagement with the feed screw, a projection carried by the feed screw nut, a rotatable spindle, a crank arm carried by said spindle and adapted to engage on the underside of the said projection, a latching means for locking the slicing table to the machine, a helical groove formed in the spindle, a projecting member having connection with the latching means and having a portion thereof adapted to engage with in the helical groove and means for imparting a rotary movement to the said spindle the movement of the said spindle in one direction simultaneously causing the crank arm to lift the feed nut free from the feed screw and causing the portion of the projecting member engaging within the helical groove to travel in the groove and to unlock the latching means.

In testimony whereof I have hereunto set my hand.

EDWIN COULSON.
